CLAMP DEVICE

Frederick Charles Schnabel, Hopkins, Minn.

Application August 13, 1937, Serial No. 159,015

1 Claim. (Cl. 24—253)

This invention relates to a clamp device, the general object of the invention being to provide a head formed to provide a jaw and a second jaw connected with the head by a spring hinge, so that the two jaws form a clamp for holding paper or the like.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing where-in like characters denote like or corresponding parts throughout the several views, and in which:

Figure 1 is an edge view of the device with the jaws closed.

Figure 2 is a similar view with the upper jaw in raised position.

Figure 3 is a top plan view of Figure 1.

Figure 4 is a perspective view with the hinged jaw removed.

Figure 5 is a perspective view of the hinged jaw.

Figure 6 is a view of the pin of the hinge.

Figure 7 is a view of the spring.

As shown in these views, the head 1 of the thumb tack is of substantially rectangular shape in cross section so as to provide straight edges which retard the tack rolling along a surface when dropped upon the surface, so that there is less danger of the improved thumb tack being lost than there is when the thumb tack is made with a round head, as usual. The tack is provided with the usual point 2 and at one edge the head on its upper face is formed with the perforated ears 3 and a groove 4 is formed in the head between the ears. The movable jaw is shown at 5 and is of substantially the same shape as the head, but one edge of the jaw 5 is formed with the perforated hinge ears or barrels 6 which partly extend into the groove 4 and abut the inner ends of the ears 3. A hinge pin 7 passes through the ears 3 and 6 and a spring 8 is placed on the pin and has a central projection 9 fitting in a recess 10 in the head 1, with the ends 11 of the spring resting on the upper face of

the jaw 5. Thus this spring tends to hold the jaw 5 against the head 1 and parts of the contacting faces of the head and jaw are roughened, as shown at 12, to increase the gripping effect of the two parts.

Thus the spring hinge tends to hold the jaw 5 against the head of the thumb tack, so that these parts will grip and hold a sheet of paper or the like.

With this invention, the thumb tack can be pressed into a drawing board or the like and the jaw and head of the tack used for holding the paper or the like, and this will permit the paper to be changed without removing the thumb tack from the board. Of course, the thumb tack can be used in the regular way, and if desired, the tack can be used in the usual manner for holding one sheet and a second sheet held by the clamp.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A device of the class described comprising a plate, perforated ears extending from one face of the plate adjacent one edge thereof and said face of the plate having a groove therein located between the ears, the ends of the groove terminating at the ears a second plate having hinge barrels extending from one edge thereof, said barrels partly fitting in the ends of the groove and having their outer ends abutting the inner ends of the ears of the first plate, a pin passing through the ears and the barrels for hinged connecting the two plates together, and a coiled spring on the pin having its ends engaging the outer face of the second plate and said spring having a central projection, the first plate having a recess therein between the groove and the adjacent edge of the plate, said recess opening into the groove and receiving said projection.

FREDERICK CHARLES SCHNABEL.
